UNITED STATES PATENT OFFICE.

GEORGE J. RATHBUN, OF TOLEDO, OHIO.

ENGINE VALVE-GEAR.

1,159,708.

Specification of Letters Patent.

Patented Nov. 9, 1915.

Application filed December 21, 1914. Serial No. 878,415.

To all whom it may concern:

Be it known that I, GEORGE J. RATHBUN, a citizen of the United States of America, and a resident of Toledo, in the county of 5 Lucas and State of Ohio, have invented certain new and useful Improvements in Engine Valve-Gear, of which the following is a specification.

My invention relates to improvements in 10 valve gear for internal combustion engines, particularly engines of the so-called four cycle type composed of two cylinders, or of multiples of two cylinder units, the cylinders of each unit placed side by side.

15 The valve gear embodying my present invention is of the roller path lever type and comprises means whereby a single reciprocating member operates the admission valves of the two cylinders in alternation, 20 and whereby another reciprocating member operates the exhaust valves of the two cylinders in alternation.

My invention consists in the novel features of construction and arrangement hereinafter described and particularly pointed 25 out in the appended claims.

The objects of my invention are to improve and simplify valve gear of engines composed of two cylinders arranged side by 30 side or of a multiple of such two cylinder units, and to provide a valve gear which is compact and smooth and silent in operation.

I will now proceed to describe my invention with reference to the accompanying 35 drawings, and will then point out the novel features in claims.

Figure 1 shows a transverse central vertical section through one of the engine cylinders of an engine of the type referred to, 40 and Fig. 2 shows a vertical section of the engine on the irregular section line $x-x$ of Fig. 1, *i. e.*, a section taken through the axes of the valve gear cross head guides, and also through the axes of the cylinders. Fig. 3 45 shows a top view of the engine.

In the drawings, numerals 1-1 designate the engine cylinders, numerals 2 the pistons, and numeral 3 the crank shaft, 4 the crank pin, and 5-5 the connecting rods.

50 6 designates a valve gear shaft driven from the crank shaft by gears 8 and 9, having the usual two to one ratio.

55 Numeral 10 designates an eccentric for operating the admission valves of the two cylinders, and numeral 11 an eccentric for operating the exhaust valves of the two cyl-

inders, both eccentrics being mounted upon the valve gear shaft 6.

Numerals 12 designate the two admission valves, and numerals 13 the two exhaust 60 valves. As will be seen, the two admission valves are set close together, the exhaust valves being to the right and left respectively of the two admission valves. The valves are all of the puppet type, and are 65 provided with the usual springs tending to hold them closed.

14 designates a valve shaft extending across the heads of the two cylinders and mounted in suitable bearing brackets 15. 70 Upon this shaft 14 is mounted loosely a double rocker comprising a hub 16 and two rocker-projections 17 and 18, one projecting to the rear and the other to the front of the engine, each of such arms 17 and 18 being 75 a roller path lever which coacts with a corresponding lever, 19 or 20, connected with the stem of one or the other of the admission valves 12. This double rocker 16-17-18 further comprises a lever arm 80 21, connected by the valve rod 22 to the piston cross head 23 working in the guide cylinder 24, and thence connected by the eccentric rod 25 to the strap surrounding eccentric 10. It will be clear that as 85 the eccentric 10 rotates and the rocker 16-17-18 is vibrated, the two admission valves, 12, will be opened in alternation.

The valve shaft 14 is provided with two rockers 26 and 27, one extending to the 90 front and the other to the rear, each being a roller path lever arranged to coact with a corresponding lever, 28 or 29, pivotally mounted, and connected to the stem of one or the other of the exhaust valves 13. 95 Shaft 14 is provided with a further lever arm 30 connected by valve rod 31 to piston cross head 32 working in guide cylinder 33, and thence by eccentric rod 34 to the eccentric strap surrounding eccentric 11. 100 It will be clear that, as the eccentric 11 rotates, the two exhaust valves will be opened in alternation. It will also be clear that, since the admission valves are operated by one eccentric, and the exhaust valves are operated by another eccentric, the timing of the exhaust valve functions may be changed as desired with reference to the admission valve functions; and vice versa. Conveniently the pivot for valve levers 19 and 29 110 may be a stationary shaft 31 mounted in suitable brackets on the cylinder heads, and

the pivot for valve levers 20 and 28 may be a corresponding fixed shaft 32 mounted in suitable brackets on the cylinder head.

While roller path levers are in themselves old, I am not aware of any prior valve gear of that type wherein a shaft, extending across the heads of two cylinders arranged side by side, and carrying roller path levers for operating two valves, has 10 pivoted on it a structure carrying roller path levers for two other valves.

It will be obvious that the valve gear herein illustrated and described is applicable to engines other than internal combustion engines of the four-cycle type; is applicable, for example, to air compressors and steam engines. I do not limit myself, therefore, to the application of my invention to internal combustion engines only.

20. What I claim is:—

1. A valve gear for engines and the like, comprising in combination a valve shaft, means for oscillating the same, and means operated by said shaft for opening and closing a plurality of valves in alternation, a member mounted for oscillation on such shaft, means for oscillating the same and means operated by such oscillatory member for opening and closing two other valves in 30 alternation.

2. An engine comprising in combination a plurality of cylinders arranged side by side, and each having a valve, a valve operating member mounted for oscillation across the heads of said cylinders, and hav-

ing roller-path levers projecting in opposite directions, means for oscillating said member and other movably mounted valve operating members engaging and coacting with said roller path levers, and also engaging 40 and adapted to operate said valves.

3. An engine comprising in combination a plurality of cylinders arranged side by side, inlet and exhaust valves for said cylinders, a valve shaft located across the heads 45 of said cylinders and mounted for oscillation, means for oscillating such shaft, roller path levers secured to said shaft and extending in opposite directions therefrom, movable valve-operating means enganging 50 and arranged to be operated by said roller path levers, and engaging and arranged to operate certain of such valves in alternation, another valve-operating member mounted for oscillation on such shaft and 55 provided with roller path levers projecting in opposite directions therefrom, means for oscillating such member, and movable valve operating means located to engage and to be actuated by the roller path levers and 60 to engage and operate in alternation others of said valves.

In testimony whereof I have signed this specification in the presence of two subscribing witnesses.

GEORGE J. RATHBUN.
